(57) **CLAIM**

The ornamental design for a machine to convert waste to energy as shown and described.

DESCRIPTION

1.1 : Front

1.2 : Back

1.3 : Top

1.4 : Right

1.5 : Left

1.6 : Bottom

1.7 : Perspective

1.8 : Perspective

The portions of the article shown in broken lines form no part of the claimed design.

Fig. **1.1** is a front view of a machine to convert waste to energy in accordance with the new design; fig. **1.2** is a back view thereof; fig. **1.3** is a top view thereof; fig. **1.4** is a right view thereof; fig. **1.5** is a left view thereof; fig. **1.6** is a bottom view thereof; fig. **1.7** is a cross-sectional view thereof; fig. **1.8** is a perspective view thereof.
